UNITED STATES PATENT OFFICE

2,666,999

EXTENSIBLE IRON STAND

Cornelius K. Brandt, Reedley, Calif.

Application November 17, 1950, Serial No. 196,323

1 Claim. (Cl. 38—107)

1 This invention relates to an extensible iron stand for attachment to an ironing board.

An object of this invention is to provide an iron stand which is particularly adapted for attachment to an end of the ironing board in a manner wherein the stand is extensible with respect to said board.

Another object of this invention is to provide an iron stand which is supported in a position overlying an ironing board contiguous to one end thereof and is movable into a position in end-to-end relation with respect to said one end of the ironing board.

A further object of this invention is to provide an extensible iron stand which is particularly adapted for quick and easy slidable attachment to an ironing board in a manner wherein the stand may be slid into a position overlying the board when the board is to be stored.

A still further object of this invention is to provide an extensible iron stand for attachment to an ironing board which is relatively simple in structure and cheap to manufacture.

The above and still further objects and advantages of the present invention will become apparent upon consideration of the following detailed description of the invention, when taken in conjunction with the accompanying drawings, wherein:

Figure 1 is a perspective view of the extensible iron stand of the present invention, shown supporting an iron and mounted on an ironing board contiguous to one end thereof;

Figure 2 is a fragmentary sectional view taken along the line 2—2 of Figure 1;

Figure 3 is a sectional view taken along the line 3—3 of Figure 1;

Figure 4 is a longitudinal sectional view, with parts broken away, of an iron cord guide and take-up shown attached to the iron stand; and

Figure 5 is an enlarged, perspective, fragmentary detail of the iron cord-engaging collar of the iron cord guide and take-up illustrated in Figure 4.

Referring now more particularly to the drawings, wherein like reference numerals have been used throughout the several views to designate like parts, there is shown the iron stand of the present invention, generally designated by the reference numeral 10, which is attached to an ironing board 11 at the end of the board remote from the pointed end thereof.

The stand 10 includes a pair of guides 15 and 16 which are arranged on opposite sides of the ironing board 11 contiguous to one end thereof

and secured to said sides. Suitable bolts 17 effect the securing of the guides 15 and 16 to the ironing board 11 with the upper side edges of the guides substantially in the plane of the top 12 of the ironing board, and with the lower side edges substantially in the plane of the bottom 13 of the ironing board 11. Contiguous to the lower side edges thereof, the guides 15 and 16 are provided with the longitudinally extending guideways 18 and 19.

Overlying the ironing board 11 at said one end thereof is an iron-supporting tray or iron stand 20 which is extensible into various positions in end-to-end relation with respect to the ironing board 11, as illustrated in Figure 1. The iron-supporting tray includes a flat iron-supporting surface 21 which is spaced above the adjacent upper surface 12 of the ironing board 11 and supports an iron 30 including an ironing cord 31.

The spacing between the iron-supporting surface 21 and the ironing board 11 provides a heat-insulated space resistant to the transfer of heat between the tray 20 and the ironing board 11. The tray 20 further includes a first end flange 22

25 dependingly secured at one end of the tray and adapted to ride along the upper surface 12 of the ironing board, and side flanges 23 and 24 likewise adapted to ride along the surface 12. The other end of the tray 20 is provided with a depending end flange 25 which is disposed in substantially spaced, parallel relation with respect to the end flange 22.

Suitable brace means are carried by each of the guides 15 and 16, and operatively connected to the iron-supporting tray for mounting the latter for extensible movement with respect to said one end of the ironing board from the storing position overlying the ironing board to the various end-to-end, aligned positions for actual use. The brace means are designated by the reference numerals 26 and 27, and each comprises an elongated rod having one end slidably received and supported within the longitudinally extending guideways 18 and 19 provided in the guides 15 and 16.

The other end of each of the rods is bent to form the brackets 28 and 29 which are engageable about the corresponding corners of the other end of the supporting tray 20. As clearly shown in Figure 2, each of the corner brackets 28 and 29 includes an upwardly opening, U-shaped clamp 33 which is engageable about the depending marginal end flange 25 of the tray 20.

Positioned contiguous to the other end of the tray is an iron cord guide and take-up, generally 55 designated by the reference numeral 35 which is

3

detachably secured to the tray 20. The iron cord guide and take-up 35 includes a supporting bracket 36 engageable about the depending end marginal flange 25 of the tray 20, the bracket 36 supporting an extensible coil spring 37 through which is extended the iron cord 31. The free end of the extensible coil spring 37 includes a collar 38 which is engageable about and securable to the ironing cord 31, as illustrated in Figure 4.

In actual use, the tray 20 can be moved to the position illustrated in Figure 1. When the tray is in this position, the major portion of the ironing board 11 can be used. In the event that the pointed end of the board is to be used, it may be desired to have the iron supported in a position somewhat closer to the pointed end. Under these conditions the tray 20 can be slid to the position overlying the end of the board remote from the pointed end. This position may also be effected when it is necessary to store the ironing board.

Although only one embodiment of the iron stand of the present invention has been described, it is readily apparent that numerous modifications can be made without departing from the spirit of the invention as set forth in the appended claim.

What I claim is:

The combination with an ironing board having a pair of guides secured on opposite sides of said

ironing board contiguous to one end thereof, of an iron-supporting tray overlying said one end of said ironing board and slidably supported on said board for movement from its position overlying said one end of said ironing board to an extended position with respect to said one end of said ironing board, and brace means slidably supported in said guides and operatively connected to said tray, each of said brace means embodying a rod having one end slidably supported within a longitudinally extending guideway provided in the respective one of said guides and having a bracket on the other end engageable about the corresponding corner of said supporting tray, the iron-supporting surface of said tray being spaced above said ironing board to provide a heat insulating space therebetween.

CORNELIUS K. BRANDT.
